My Undivided Assignee

David S. Gilmore of same place.

Letter Patent No. 2428. Dated Sept. 25. 1866.

Design for a Picture Frame.

The schedule referred to in these Letters Patent and making part of the same

To all whom it may concern:

Be it known that I, John H. Bellamy of Charlestown in the County of Middlesex, and State of Massachusetts have invented or produced a New and Original Design for a Picture Frame; and I do hereby declare that the following is a full and exact description of the same.

The nature of my invention consists of a new and original Design for a Picture Frame, as follows to wit: The frame, for containing the picture is ornamental at the top centre with a scroll 1. broken which are the square 2. and a compass 3. enclosing the letter G, 4. the whole being supported by scroll work B. On the left of the frame are two perpendicular parallel lines 5. enclosing a circle 6. and book 7. and on the right a three pronged ladder 8. at the bottom center are the twenty four inch gauge 9. and the gauge 10. together with a level 11. on the right of which is a scroll C. enclosing a square 12. and on the left a scroll D. enclosing a plumb 13. the whole being substantially as for the invention.

What I claim as my invention and desire to secure by Letters Patent is: The Design for a Picture Frame substantially as shown and described.

Witnesses,

Chas D. Denton.
